CONTROL MECHANISM FOR FLUID MOTORS

John E. Goodwillie and Alonzo A. Neese, Beloit,
Wis., assignors to Beloit Iron Works, Beloit,
Wis., a corporation of Wisconsin

Application July 2, 1947, Serial No. 758,568

3 Claims. (Cl. 60—97)

1

This invention relates to a control mechanism for equalizing movements of the output members of fluid motors, and particularly to control mechanisms for roll positioning fluid motors for paper making machines which will insure that the associated roll is uniformly moved into a nip defining position with respect to another roll to provide simultaneous contact along the entire length of the nip defined by the two rolls.

In paper making machines, rolls of substantial size are commonly employed and it is frequently desirable that such massive rolls be moved into a nip defining position with respect to another roll while one or both of such rolls are rotating. To accomplish such movement, a plurality of fluid motors, such as the piston and cylinder type, are employed to move one roll in contact with another and then to apply pressure to the nip thus defined. If, as frequently happens, the output member of one fluid motor moves ahead of the output member of the other motor, then one end of the roll will come into contact with the co-operating roll before the other end. Since the rotating speeds of the two rolls will not be exactly the same before contact, a felt or paper web running on either of the rolls will be twisted when a partial contact is made. This twist is often powerful enough to tear the felt off the machine and to damage the rubber cover on one of the rolls. In any case, an uneven contact will twist the felt seam and make it tend to move toward one side of the machine during subsequent running.

Heretofore the solution of this problem has been attempted through the medium of mechanical ties between the roll support arms on which the individual fluid motors work in an attempt to force the fluid motors to move equally. However, due to the size of the rolls and particularly the great axial length of such rolls, it is often difficult and quite expensive to obtain a sufficiently stiff cross shaft to insure equal movements of the roll positioning fluid motors.

Accordingly, it is an object of this invention to provide an improved control mechanism for a plurality of fluid motors to insure simultaneous and equal movements of the output members of such motors.

Another object of this invention is to provide an improved control mechanism for the roll positioning fluid motors of a paper making machine or the like by which a roll moved by a plurality of fluid motors may be uniformly advanced into a nip defining position with respect to another roll.

A particular object of this invention is to provide improved control arrangements for supplying fluid to a plurality of fluid operated motors having output members movable to and from a predetermined position in such a manner that

unequal movements of the output members to their respective predetermined positions produce unequal fluid flow to the fluid motors tending to equalize the displacements of the output members from such predetermined positions.

A particular object of this invention is to provide an improved fluid supply control mechanism for a pair of fluid motors respectively connected to independently movable roll support members 10 wherein a valve is associated with each of the motors for controlling the supply of fluid thereto and the shiftable member of such valve is connected by linkages to the respective support arms so that movements of such support arms control the flow of fluid through the respective valve member, and particularly, so that unequal movements of the support arms produce unequal fluid flow through the valve members tending to equalize the movements of the supports.

20 The specific nature of this invention, as well as other objects and advantages thereof, will become apparent to those skilled in the art from the following detailed description of the annexed sheets of drawings which, by way of preferred examples 25 only, illustrate three specific embodiments of this invention.

On the drawings:

Figure 1 is a schematic perspective view of an assembly of elements embodying this invention 30 illustrated in connection with a roll positioning mechanism for a paper making machine;

Figure 2 is a schematic perspective view of a modified form of this invention again shown as applied to the roll positioning mechanism of a 35 paper making machine;

Figure 3 is an enlarged scale, schematic view of the valve unit employed in the assembly of Figure 2;

Figure 4 is a schematic perspective view of a 40 third modification of this invention, again shown as applied to the roll positioning mechanism of a paper making machine;

Figure 5 is a perspective view illustrating a 45 preferred mechanical connection of the two selector valves employed in the mechanism of Figure 4; and

Figure 6 is a partial sectional view taken along the plane VI—VI of Figure 4.

As shown on the drawings:

50 While this invention will be particularly described and illustrated in connection with its application to a roll positioning mechanism of a paper making machine, it should be understood that the invention is not so limited but may be 55 applied to any apparatus wherein equal movements of the output members of a plurality of fluid motors are required.

Referring to the drawings, the numerals 1 and 60 2 illustrate a pair of rolls for a paper making

machine or the like which are relatively movable so that they may be brought into juxtaposition to define a pressure nip therebetween. In the following description, it will be assumed that the roll 1 is fixed and the roll 2 is movable but it should be understood that this is merely for purposes of example and both rolls could be movable with respect to each other without affecting the operation or the desirable features of this invention.

The movement of movable roll 2 is accomplished by a pair of support arms 10, each of which is pivotally mounted on a fixed bracket 12 by a pin 14. A bearing block 16 is medially positioned on each support arm 10 and journals the shaft 18 for the movable roll 2. The free ends of the support arms 10 are respectively connected to the output members 20 of a pair of fluid motors 5. While not limited thereto, fluid motors 5 are schematically illustrated as comprising a cylinder casing 22 within which a piston 24 is reciprocable and secured to output shaft 20. A fluid inlet port 26 is provided in cylinder casing 22 on one side of piston 24 and an exhaust port 28 is provided on the other side.

From the foregoing description, it is apparent that the support arms 10 are gravitationally biased to a position wherein the movable roll 2 is removed from contact with fixed roll 1. However, application of a suitable fluid under pressure to the cylinder casing 22 through inlet port 26 will produce an upward movement of piston 24 and hence move roll 2 towards a nip defining position with respect to fixed roll 1.

It will be understood by those skilled in the art that the support arms 10 are substantially independently movable inasmuch as they are only coupled by the roll 2 journaled thereon. The roll 2 is generally of such construction as to not to provide a rigid tie between the support arms 10 and hence in accordance with this invention, the supply of fluid respectively to the fluid motors 5 is controlled to insure substantially equal movement of the support arms 10 toward the nip defining position of the movable roll 2 so that the movable roll 2 will contact the fixed roll 1 substantially concurrently along the full length of the roll.

Conduits 30 are provided respectively connecting with inlet 26 for the supply of fluid to the fluid motors 5. At an intermediate point in the conduits 30 there are provided pressure regulators 32 which are not illustrated in detail in as much as they comprise any conventional form of pressure regulating valves by which the maximum pressure transmitted to the fluid motors 5 may be manually adjusted.

Conduits 30 respectively communicate with output ports 34b and 34d of a selector valve unit 34. Selector valve unit 34 also is provided with inlet ports 34a and 34c which are respectively connected by conduits 36 to two outlet ports 38a and 38b of a regulating valve 38.

Selector valve 34 may comprise any one of several well known constructions and includes a shiftable plug member 36 having fluid flow passages 36a and 36b therein which may be respectively connected between one of the inlet ports and another one of the outlet ports of selector valve 34. Plug member 36 is manually shiftable by handle 37 and has at least two operative positions. In one such position, inlet port 34a is connected to outlet port 34b while inlet port 34c is connected to outlet port 34d. In the other position of shiftable plug member 36, inlet port 34a

is in fluid communication with outlet port 34d, while inlet port 34c is in fluid communication with outlet port 34b. Hence, the operation of selector valve 34 effectively interchanges the connections of fluid motor inlets 26 with respect to the outlet ports 38a and 38b of regulating valve 38.

While regulating valve 38 has been illustrated as being of the sliding piston type, it will be 10 recognized that other well known forms of valves may be substituted therefor. Regulating valve 38 comprises a cylindrical casing within which a piston member 40 is reciprocable. An inlet port 38c is provided in the casing and a conduit 42 connects inlet port 38c with the outlet port of a 15 two position selector valve 44. The two inlet ports of selector valve 44 are respectively connected to a supply source of pressurized fluid and to an exhaust conduit. Hence inlet port 38c of 20 regulating valve 38 may be selectively connected to either a relatively high pressure fluid source or to a low pressure exhaust conduit by manual operation of the control hand 46 of selector valve 44.

25 The piston 40 of regulating valve 38 in reality comprises two axially spaced piston members 40a and 40b which cooperate with the two outlet ports 38a and 38b to selectively connect either one of such ports or both of the ports in fluid 30 communication with inlet port 38c, depending upon the axial position of piston 40. The normal position of piston 40 is as illustrated in Figure 1 wherein both of the outlet ports 38a and 38b are disposed in equal fluid communication 35 with inlet port 38c. Hence, the fluid motors 5 will receive or discharge equal amounts of fluid. However, any movement of the piston 40 from such normal position will rapidly cut off the fluid supply or discharge from one of the fluid motors 40 5, the particular fluid motor 5 affected being determined by the direction of displacement of the piston 40.

The displacement of piston 40 of regulating valve 38 is controlled as a function of unequal 45 movements of the support arms 10 by a linkage indicated generally by the numeral 50. Such linkage may obviously take a variety of well known forms. The particular type illustrated 50 comprises an operating link 52 which is medially pivoted to the end of the rod 48 of piston 40. One end of operating link 52 is pivotally connected by a link 54 to an integral arm portion 11 provided on one of the bearing support arms 10. The other end of operating link 52 is connected to the other support arm 10 through a linkage including arm 55, cross shaft 56, arm 58, and adjustable link 60. Adjustable link 60 may 55 conveniently comprise a pair of rods 60a and 60b having their adjacent ends threaded and adjustably connected by a nut member 60c.

The effective length of adjustable link 60 is selected so that equal movements of the bearing 60 support arms 10 will produce equal but opposite pivotal movement of the ends of operating link 52 about its medial pivot on piston rod 48. Hence, so long as the bearing support arms 10 move equally and uniformly, no displacement of the piston 40 will be effected. However, when 65 for any reason one support arm 10 moves faster than the other arm, the operating link 52 will produce a displacement of piston 40 which will be in the direction to modify the flow of fluid to or from one of the fluid motors 5 so as to equalize 70 the movement of bearing support arms 10. This 75 action is of course equivalent to equalizing the

movements of the output shaft members 20 of the fluid motors 5.

The control mechanism heretofore described will uniformly move the support arm 10 both toward and away from the nip defining position of the movable roll 2. To move the roll 2 into engagement with fixed roll 1, the selector valve 44 is manipulated to connect inlet 38c of regulating valve 38 with the source of high pressure fluid. Selector valve 34 is manipulated to connect outlet ports 34b and 34d respectively with inlet ports 34a and 34c, as illustrated in Figure 1. With such adjustments, fluid will be supplied to both of the fluid motors 5 in such a manner as to uniformly move the varying support arms 10 to their nip defining positions.

To retract the support arms 10 from the nip defining positions, the selector valve 44 is operated to connect inlet port 38c of regulating valve 38 with the low pressure exhaust conduit and the plug 36 of selector valve 34 is shifted to effect a reversal of connections of the inlet 26 of the fluid motors 5 with respect to outlet ports 38a and 38b of regulating valve 38. Hence the fluid in the cylinder casings 22 of the fluid motors 5 is permitted to exhaust through selector valve 34, regulating valve 38 and selector valve 44. Such fluid is of course forced out of casings 22 by the gravitational bias produced by the weight of support arms 10 and associated apparatus upon the pistons 24. The piston 40 of regulating valve 38 will nevertheless control the rate of exhaust from each of the fluid motors 5 to maintain uniform the retracting movements of the support arms 10.

When the support arms 10 are moved to their nip defining positions, it is apparent that the nip pressure between the rolls 2 and 1 may be conveniently adjusted by operation of pressure regulator valve 32 and that such adjustment of the nip pressure is entirely independent of the control mechanism by which uniformity of movement of the support arms 10 is obtained.

Referring to Figure 2, there is shown a fluid control mechanism constituting a modification of this invention. In this modification, wherein similar numerals refer to elements corresponding to those of Figure 1, a pair of independently movable support arms 10 are again provided to journal the movable roll 2 and position such roll with respect to the fixed roll 1. A pair of fluid motors 5 are also provided for positioning the support arm 10. In this modification, the cylinder casings 22 of the fluid motors are provided with ports 62 and 64, respectively, disposed below and above the piston 24. A control valve unit 70 and an operating linkage 80 is provided for each of the fluid motors 5. Since such mechanisms are identical, only one will be described in detail.

Each control valve unit 70 may conveniently comprise a selector valve having four ports 70a, 70b, 70c, and 70d, respectively (Fig. 3). The ports 70b and 70d are respectively connected by conduits 72 to ports 62 and 64 in the associated fluid motor 5. Port 70a is connected by conduit 73 through pressure regulating valve 32 to a source of high pressure fluid while the port 70c is connected to an exhaust conduit 75.

Each valve unit 70 is provided with a shiftable plug member 76 which has suitable passages 76a, 76b, 76c, and 76d, therein to selectively provide fluid communication between the various ports of the selector valve. Preferably the passages in the shiftable plug member are arranged in a

manner similar to that illustrated in Figure 3, each passage having openings 90° displaced from each other. Each of the openings of the various passages 76a through 76d are, however, preferably equispaced from each other around the periphery of the shiftable plug member 76. Hence, as shown in Figure 3, the passage 76d is aligned with the ports 70a and 70d when the passage 76b is aligned with ports 70b and 70c. In this same position, passages 76a and 76c are closed at both ends. Hence, rotation of the shiftable plug member 76 in either direction from the position shown in Figure 3 will effect first a reduction in fluid flow through ports 62 and 64 of the fluid motor 5, then a complete interruption of fluid flow, and finally, upon still further shifting of the plug member 76, the passage 76a will align with ports 70a and 70b and the passage 76c will align with ports 70c and 70d, and hence a reversal of direction of fluid flow into the casing of fluid motor 5 will result.

The control linkage 80 by which the valve unit 70 is operated comprises an arm 82 which is suitably secured to the shiftable plug member 76. A link 84 is pivotally mounted to the end of arm 82 and the other end of link 84 is pivotally joined to a pivotal connection between a main link 86 and an adjustable link 88. Adjustable link 88 is extensible or retractable by any suitable threaded arrangement indicated generally by the numeral 88a which may be adjusted by rotation of a pinion 88b associated therewith.

To produce concurrent adjustment of adjustable link 88 of each of the control linkages 80, a cross shaft 90 is provided having a pair of worms 92 respectively engageable with the adjusting pinions 88b. Cross shaft 90 is in turn manually adjustable by hand wheel 94.

The shiftable plug member 76 is shown in Figure 3 in the position which it occupies when the bearing support arms 10 are in their remote position with respect to the fixed roll 1. To produce uniform movement of the bearing support arms 10 to their nip defining positions with respect to the fixed roll 1, the adjustable links 88 are concurrently lengthened by rotation of hand wheel 94. This produces a counterclockwise shifting of the shiftable plugs 76 and, if hand wheel 94 is rotated enough, will result in the alignment of passage 76a in the shiftable plug 76 with ports 70a and 70b and passage 76c with ports 70c and 70d. Hence, fluid will be supplied from the fluid source through the ports 62 in the casing of each fluid motor 5 beneath the piston and concurrently, fluid will be exhausted through the ports 64 from above the piston. Hence an upward movement of pistons 24 results and accordingly, the support arms 10 are moved toward their nip defining positions.

It should be noted that such upward movement of support arms 10 produces through controlling linkage 80 a clockwise rotation of the shiftable plug member 76. Such clockwise shifting of the plug member 76 gradually decreases the flow of fluid to the fluid motors 5 and will completely cutoff such flow if the adjustable links 88 are not further lengthened. Hence, even though one support arm 10 is moved more rapidly by its fluid motor 5 than the other, the effect of such movement will be to cutoff the actuating fluid supplied to such fluid motor sooner, whereupon all movement of the fast fluid motor ceases. Meanwhile, fluid is still being supplied to the slower fluid motor 5 and it catches up with the faster

fluid motor 5 and automatically effects the cut-off of fluid supply to itself.

It is therefore apparent that so long as the hand wheel 94 is rotated to effect a lengthening of the adjustable link 88, the fluid motors 5 will produce a substantially uniform and equal movement of the support arms 10 toward their nip defining position. Once the roll 2 arrives at its nip defining position, the hand wheel 94 need only be rotated sufficiently to insure that the passages 76a and 76c are in alignment respectively between ports 70a and 70b and ports 70c and 70d. Thereafter, the effective force applied to the nip by the fluid motors 5 is controlled by the fluid pressure regulators 32.

To retract the support arms 10 from their nip defining positions, the hand wheel 94 is rotated in the opposite direction which has the effect of shortening the adjustable link 88. Such shortening of link 88 in turn produces a clockwise shifting of the shiftable plug members 76 and hence the fluid connections to the fluid motors 5 are reversed, high pressure fluid being supplied to port 64 and fluid being withdrawn to exhaust from port 62. Hence the pistons 24 will be urged downwardly and the support arms 10 will be lowered. Such lowering movement of the support arms 10 will however occur uniformly for the same reasons as were heretofore described in connection with the raising movement. Any tendency of one fluid motor to operate faster than the other effects a more rapid cutoff of the actuating fluid supplied to the faster motor, permitting the slower motor to catch up.

In the modifications of Figures 1 and 2 heretofore described, the movements of the output members of the pair of fluid motors was maintained substantially uniform throughout the entire stroke of such motors and in both directions. In the modification of this invention shown in Figures 4 through 6, the movements of the fluid motors are equalized at only one point, which point may correspond to the support arms arriving at a certain minimum displacement from their nip defining positions.

The fixed roll 1, movable roll 2, support arms 10, and fluid motors 5 for actuating the support arms are again provided in this modification in the same manner as was heretofore described. However, each fluid motor 5 has a cutoff valve 100 associated therewith. Cutoff valve 100 may conveniently comprise a cylindrical casing 102 within which a piston 104 is reciprocable. An adjustable link 106 connects each piston 104 to a fixed arm 108 provided on the corresponding support arm 10. Adjustable link 106 preferably comprises a pair of rods having their adjacent ends threaded, as indicated at 106a, and engaged by a nut member 106b.

Each cutoff valve 100 has a pair of ports 110 (Fig. 6) provided therein, which are arranged to be concurrently cutoff by the movement of the piston 106 produced by the movement of the respective support arm 10 toward its nip defining position. The adjustable links 106 are adjusted so that such cutoff action occurs when each support arm 10 has obtained the same displacement from its nip defining position, preferably a short distance therefrom.

Actuating fluid for each fluid motor 5 is respectively supplied to the inlet port 26 in the casing of such motor through a selector valve 114. A conduit 116 connects inlet port 26 with port 114c of selector valve 114 through pressure regulator 32. Port 114a of selector valve 114 is connected

by conduit 118 to a suitable source of high pressure fluid while port 114b is connected to a low pressure exhaust conduit 115. Selector valve port 114d is connected by conduit 120 to one of the ports 110 provided in cutoff valve 100. The other port 110 in each cutoff valve 100 is connected by conduit 122 to the supply source of high pressure fluid. The shiftable plug member 124 for each of the selector valves 114 is provided with two passages 124a and 124b. Such passages are suitably arranged so that in one position, for example, the position illustrated in Figure 4, the passage 124a provides fluid communication between selector valve ports 114d and 114c, while the passage 124b is closed. In another position of the shiftable plug 124, passage 124b provides fluid communication between selector valve ports 114a and 114c while the passage 124a is closed.

It is desirable that the shiftable plug members 124 of each selector valve 114 be operated simultaneously. Accordingly, the arrangement illustrated in Figure 5 will conveniently permit such condition to be obtained. The selector valves 114 are disposed in superposed relationship and a common operating shaft 126 is suitably connected to both of the shiftable plug members 124 and is rotatable by a handle 128.

In the operation of this modification of this invention, the control handle 128 is manipulated to place the shiftable plug members 124 in the positions illustrated in Figure 4. In such positions, actuating fluid is supplied to both of the fluid motors 5 through their inlet ports 26, and the pistons 24 of such motors will be moved upwardly, thus moving the bearing support arms 10 toward their nip defining positions. When each bearing support arm reaches a certain predetermined minimum displacement from its nip defining position, the piston 104 of the respective cutoff valve 100 overrides the cutoff ports 110 and thus completely interrupts the supply of actuating fluid to the associated fluid motor 5. Hence, irrespective of the speed of operation of the fluid motors 5, both motors are stopped when they arrive at the same predetermined displacement from their nip defining positions.

The movement of the roll 2 into engagement with roll 1 may then be completed by manipulation of handle 128 to position the shiftable plug members 124 in a second position wherein plug passage 124b is disposed in fluid communication between selector valve ports 114a and 114c. In this position, the cutoff valves 100 are by-passed and the actuating fluid is supplied directly to both of the fluid motors 5. Since the support arms 10 are preferably stopped by operation of cutoff valves 100 at a very short distance from their nip defining positions, the remaining movement of the fluid motors 5, from the cutoff point to the nip defining point, is a sufficiently short distance that differences in speed of the fluid motors 5 are substantially negligible, and the movable roll 2 will be brought into substantially uniform engagement with the fixed roll 1. In this position, the pressure on the nip may be conveniently varied by operation of pressure regulators 32.

To retract the movable roll 2 from its nip defining position, the shiftable plugs 124 are moved to a third position wherein the passage 124a is disposed in fluid communication between selector valve ports 114b and 114c. This permits the fluid in fluid motors 5 to be forced out of the fluid motor casing into the exhaust conduit 115 by the gravitational bias exerted on such fluid

motors by the support arms 10 and the weight of the mechanism associated therewith.

It is therefore apparent that each of the described modifications of this invention provides control mechanism for a plurality of fluid motors which insures that the output members of such motors will move uniformly and simultaneously to a predetermined position and hence, when applied to a roll positioning device for a paper making machine, insures that contact between a movable and fixed roll will occur substantially concurrently along the entire length of the rolls, thereby avoiding any possibility of damage to the rolls or to any felt or web trained on such rolls.

It will, of course, be understood that various details in construction may be varied over a wide range without departing from the principles of this invention and it is, therefore, not the purpose to limit the patent granted hereon otherwise than necessitated by the scope of the appended claims.

We claim as our invention:

1. In combination, a pair of spaced, independently movable roll support members, a roll journaled on said support members and movable thereby to and from a nip defining position with respect to another roll, a fluid pressure motor for moving each of said support members, a control valve having an inlet connected with a source of fluid pressure and a pair of outlets respectively connected to said fluid pressure motors, a first selector valve arranged to selectively connect said inlet to a fluid pressure source or to a fluid exhaust conduit, a flow control member movable in said control valve to selectively connect either one or both of said outlets to said inlet, linkage means controlling the position of said flow control member as a function of unequal displacement of said roll support members from their nip defining positions to supply relatively more fluid to the fluid pressure motor associated with the slower moving member, thereby insuring substantially concurrent movements of said support members, and a second selector valve connected between said outlets and said fluid motor means, said second selector valve being constructed and arranged to interchange connections between said outlets and said fluid motors, whereby the manipulation of said first and second selector valves between their two positions respectively move said support members uniformly toward and away from their nip defining positions.

2. In combination, a pair of spaced, independently movable roll support members, a roll journaled on said support members and movable thereby into a nip defining position with respect to another roll, a fluid pressure motor for moving each of said support members, said support members being arranged with respect to said fluid pressure motors so as to gravitationally bias said motors toward positions remote from said nip defining position, a control valve having an inlet with a source of fluid pressure and a pair of outlets respectively connected to said fluid pressure motors, a first selector valve arranged to selectively connect said inlet to a fluid pressure source or to a fluid exhaust conduit, a second selector valve connected between said outlets and said fluid motors, said second selector valve being constructed and arranged to interchange connections between said outlets and fluid motors, whereby the manipulation of said first and second selector valves between their two positions respectively

move said support members toward and away from their nip defining positions, a flow control member movable in said control valve to selectively connect either one or both of said outlets to said inlet, and linkage means controlling the position of said flow control member as a function of unequal displacements of said roll support members from their nip defining positions to maintain relatively more fluid in the fluid pressure motor associated with the support member having the greater displacement, thereby insuring substantially concurrent movements of said support members to and from their nip defining positions.

3. In combination, a pair of spaced, independently movable roll support members, a roll journaled on said support members and movable thereby into a nip defining position with respect to another roll, a fluid pressure motor for moving each of said support members, a control valve having an inlet and a pair of outlets, a first selector valve arranged to selectively connect said inlet to a fluid pressure source or to an exhaust conduit, a second selector valve connected between said outlet and said fluid motors, said second selector valve being constructed and arranged to interchange connection between said outlets and said fluid motors, a flow control member slidably movable in said control valve to selectively connect either one or both of said outlets to said inlet, an operating link, said flow control member being medially pivoted to said operating link, a first linkage connecting one end of said operating link to move as a function of the movement of one of said support members, a second linkage connecting the other end of said operating link to move as a function of the movement of said other support members, said first and second linkages being constructed and arranged to produce equal and opposite pivotal displacement of the ends of said operating link for equal movements of said support members, but to shift said control valve when said support members are unequally displaced from their nip defining positions, whereby the sliding movement of said control valve member supplies more fluid to that fluid motor associated with the support member having the greater displacement from said nip defining positions, and whereby the manipulation of said first and second selector valves between their two positions respectively moves said support members uniformly toward and away from their nip defining positions.
